SPIKE SETTING DEVICE
Lloyd E. Moss, 1912 Offey St., Perry, Iowa
Filed May 17, 1961, Ser. No. 110,672
11 Claims. (Cl. 1—1)

My invention relates to the art of installing railroad spikes and more particularly to a device for setting and holding the spike during the initial phase of the driving operation.

Despite the great advances in railroading science, nothing has yet replaced the common railroad spike. Pneumatic and hydraulic hammers have been devised to replace the hand sledge in the spike driving operation, but the spikes are still positioned by hand and the initial driving operation is still accomplished by a hand tool.

Therefore, the principal object of my invention is to provide a spike setting device that will grasp and then deliver the spike to its driving position; then hold the spike as the driving operation begins, and then release the spike and withdraw from the spike driving area.

A further object of my invention is to provide a spike setting device that can be easily controlled and which can be easily adapted to either automatic or manual control.

A still further object of my invention is to provide a spike setting machine that is economical of manufacture and durable in use.

These and other objects will be apparent to those skilled in the art.

My invention consists in the construction, arrangements, and combination, of the various parts of the device, whereby the objects contemplated are attained as hereinafter more fully set forth, specifically pointed out in my claims, and illustrated in the accompanying drawings, in which:

FIG. 1 is an elevational view of my device;

FIG. 2 is an elevational view of my device taken at right angles to the view in FIG. 1 and showing the two-way control cylinder thereof;

FIG. 3 is a sectional view taken on line 3—3 of FIG. 1;

FIG. 4 is a sectional view of my device taken on line 4—4 of FIG. 3 and shows the spike-gripping jaws thereof;

FIG. 5 is a sectional view of the control means as taken on line 5—5 of FIG. 6;

FIG. 6 is a perspective view of the control means of my device; and

FIG. 7 is a perspective view of my device mounted on a railroad vehicle.

In FIG. 7 I have used the numerals 10 and 12 to designate two conventional rails mounted on ties 14. A conventional service vehicle 16 with wheels 18 is mounted on rails 10 and 12 and is powered by motor 20. Motor 20 is operatively connected to compressor 22 to provide a supply of compressed air. A conventional pneumatic hammer 24 is movably secured to the forward end of vehicle 16. The connecting means between the vehicle and hammer can permit the transverse sliding of the hammer from one side of the vehicle to the other across the forward end thereof to permit the hammer to drive spikes on either side of both rails 10 and 12. Hammer 24 is also adapted for vertical movement so that it can move downward with a spike as the spike is being driven into a tie. Since the precise details of the hammer and its securing means are not an integral part of the invention herein claimed, the structural details of these components have not been shown.

Base plate 26 is shown in FIG. 3 and parallel spaced apart side plates 28 and 30 are welded or otherwise secured to the edges of the base plate. A pin 32 spans the distance between the two plates and is secured to the

2

plates at their outer free edges, and a spacer element 34 is mounted on pin 32 to stabilize the plates at these points and maintain the parallel relationship therebetween. Plate 26 can be rigidly detachably secured to hammer 24 by brackets 35.

A vertical feed tube 36 is welded or otherwise secured to base plate 26 intermediate plates 28 and 30 and extends from the top of plate 26 downwardly to approximately the center thereof. Tube 36 is oval-shaped in cross section and terminates in a spike guide 38. Spike guide 38 is comprised of a semi-circular funnel element 40 which is secured to the top of a substantially U-shaped bar 42. Bar 42 has a bottom 44 (see FIGS. 1, 2 and 3), upper side portions 46 (see FIG. 3), and lower side portions 48 (see FIGS. 1 and 2). A gap appears between the side portions 46 and 48 at 50 for a reason to be discussed hereafter. A stop element 52 is secured to the lower end of bar 42 as shown in FIGS. 1 and 2. A spike 54 with head 55, shank 56, and point 57, can be dropped downwardly through tube 36, and the spike will then be received by the spike guide 38 with the shank 56 resting in U-shaped bar 42; the head dwelling in funnel element 40; and the point 57 resting on stop element 52.

A double acting air cylinder 60 is mounted in a vertical position on plate 30 by means of brackets 62. Piston 63 is slidably mounted within cylinder 60 and piston rod 64 extends downwardly therefrom. An elongated bar 66 is secured to the lower end of piston rod 64 by means of clamp 65. Bar 66 extends vertically downwardly in sliding relationship through bearing 67 and has a plurality of gear teeth 68 on one of its surfaces. Bearing 69 is secured in any convenient manner to plate 30. Stop element 69A on the lower end of bar 66 limits the upward travel of the bar through the bearing 69. A horizontal shaft 70 has one of its ends journaled in bearing 67 and its other end protrudes through and is rotatably supported by plate 30. A gear 72 is rigidly secured to shaft 70 between bearing 67 and plate 30 and the teeth of gear 72 are meshed with the teeth of bar 66 so that the rectilinear displacement of the bar will impart rotational movement to the gear. An arm 74 (see FIGS. 1 and 3) is rigidly secured to shaft 70 and has an elongated slot 75 extending substantially its entire length.

Each of the plates 28 and 30 has a straight elongated slot 76 diagonally disposed in the upper portions thereof as shown in FIGS. 2 and 3. A C-shaped slot 78 appears in the lower portions of these same plates as also shown in FIGS. 2 and 3. Two inverted T-shaped arms 80 form a carriage 80A and are held in parallel spaced relationship by bracket 81. Guide pins 82 are rigidly secured to the upper ends of arms 80 and extend through slots 76 in plates 28 and 30. Flanged bushings 84 on pins 82 also extend through these slots to permit easy movement of the arms 80 with respect to the slots. Guide pins 86 and flanged bushings 88 on the lower portions of arms 80 perform the same function with respect to the C-shaped slots 78 as pins 82 and bushings 84 did with respect to slots 76. As shown in FIGS. 1 and 3, the slot 75 in arm 74 also receives one of the pins 86 and one of the flanged bushings 88 on the lower end of one of the arms 80 so that the arm 74 can impart movement to arms 80 with respect to slots 76 and 78.

A normally horizontal air cylinder 90 is secured between the normally horizontal lower portions 92 of inverted T-shaped arms 80 by means of clip 94, as shown in FIG. 4. Piston 95 is slidably mounted in cylinder 90 and piston rod 96 extends from one end of the cylinder to terminate in the frusto-conically shaped plunger head 97. Spring 98 is mounted within the cylinder 90 between one end of the cylinder and piston 95 to yieldably force the piston toward air port 99 which, in turn, normally tends to withdraw piston rod 96 into the cylinder. Two

separate fingers 100 are pivotally secured to bracket 81 by means of pins 102. Each finger 100 has a recess 103 which is located away from plunger head 97 at a point beyond pins 102. A gripping portion 104 on each of the fingers 100 extends beyond the inverted T-shaped arms 80 and a spring 106 which has its ends journaled in recesses 103 normally causes the gripping portions of the fingers to pivot away from each other. Plunger head 97 is adapted to engage the tapered ends 107 of fingers 100 to urge the gripping portions 104 of the fingers together whenever air is forced into cylinder 90 through air port 99 to cause piston 95 to overcome spring 98. In FIG. 4, a spike 54 is shown held by fingers 100 when compressed air is being introduced into cylinder 90. A semi-circular funnel element 108 is secured to the top of bracket 81, as shown in FIG. 3, and extends above fingers 100 to loosely embrace in spaced relationship the spike 54 which is held by the fingers. When the inverted T-shaped arms 80 are in their uppermost positions, as shown in FIGS. 1 and 2, the funnel shaped elements 49 and 108 tend to guide the point 57 and shank 56 of spike 54 into the U-shaped bar 42. At the same time, the gripping portions 104 of the fingers 100 are adjacent the gap 50 (see FIG. 1) in the sides of the spike guide 38 so that they are free to grasp a spike that may be deposited within the U-shaped bar 42.

A control valve 110 is secured to the service vehicle 16 by means of bracket 111. A conduit 112 connects compressor 22 with air port 113 on valve 110 which in turn is in communication with a center bore 114 in the valve. Pistons 115 and 116 are slidably mounted within bore 114 and are rigidly secured to rod 117 which protrudes from one end of the bore. Bracket 118 is secured to the bottom of valve 110 and has a slot 119 which receives lever 120, which is secured to the protruding end of rod 117. Slot 119 serves to limit the displacement of rod 117 within bore 114. Spaced apart air ports 121 and 122 in valve 110 are in communication with bore 114 and the manual displacement of the two pistons can either close the ports, or can direct compressed air into one port or the other. The spaced apart distance between pistons 115 and 116 is the same as that between ports 121 and 122.

An air block 124 is secured in any convenient manner to plate 28 and has air ports 125, 126, 127, 128 and 129. As shown by the dotted lines in FIG. 6, ports 125 and 126 are in communication with each other by means of duct 36. Ports 127, 128 and 129 are in communication with each other by means of ducts 131, 132 and 133. Conduit 134 connects port 121 in valve 110 and port 125 in block 124. Conduit 135 connects port 122 in valve 110 and port 127 in block 124. Conduit 136 connects port 126 in block 124 with air port 137 on cylinder 60, and conduit 138 connects air port 129 in block 124 with port 139 on cylinder 60. Conduit 140 connects port 99 on cylinder 90 with a flexible conduit 141, which in turn is connected to air port 128 on block 124. Conduit 140 can be welded or otherwise secured to one of the inverted T-shaped arms 80.

The normal operation of my device is as follows: With my device mounted on the air hammer 24 and the hammer mounted on the service vehicle 16 as described, the hammer and its driving element 142 are positioned over the point where a spike is to be driven. The pistons 115 and 116 in control valve 110 can be moved so that air port 121 is positioned therebetween. This will allow compressed air to move from the compressor 22, thence through conduit 112, port 113, bore 114, port 121, conduit 134, port 125, duct 130 in block 124, port 126, conduit 136, port 137 in cylinder 60, which will cause the rod 64 to move downwardly out of the cylinder. This will cause bar 66 to rotate gear 72, shaft 70 and arm 74 in a clockwise direction, as viewed in FIGS. 2 and 3, which will in turn force the inverted T-shaped arms 80 to move to their uppermost positions in slots 76 and 78,

as shown in FIG. 1. The position of carriage 80A will place the fingers 100 on the arm 80 in the position described above with respect to the spike guide 38 whereby the fingers could grasp a spike which was received in the spike guide apparatus. At this point, the fingers 100 are in their "relaxed" position shown by the dotted lines in FIG. 4.

A spike 54 can then be introduced into the tube 36 and spike guide 38 in the manner described, and the control valve 110 can then be actuated so that port 122 is located between pistons 115 and 116. This allows the compressed air in the top end of the cylinder 60 to reverse its path and be exhausted out of the open end of bore 114 in valve 110 which is beyond piston 115. The compressed air thereupon moves into port 122 instead of port 121, and thence through conduit 135 to port 127 in block 124. The air then moves into duct 131 and thence moves in opposite directions through duct 133. This simultaneously supplies compressed air to the lower end of cylinder 60 (through conduit 138 and port 139 in the cylinder) and the port 99 on cylinder 90 (through duct 132, flexible conduit 141, and conduit 140). The compressed air entering cylinder 90 causes fingers 100 to grip the shank of the spike 54 in the manner described. The supply of air to the lower end of cylinder 60 causes the rod 64 and bar 66 to move upwardly. This induces a counter-clockwise rotation of the gear 72, shaft 70, and arm 74, as viewed in FIGS. 2 and 3, which causes the carriage 80A formed by arms 80 to move from the upward position in slots 76 and 78 (see FIGS. 1 and 2) to the lowermost position of the carriage, as shown in FIG. 3. The spike 54 is therefore withdrawn from the spike guide and moved downwardly and underneath the driving element 142, of hammer 24. Stop element 69A on the lower end of bar 66 will engage bearing element 69 as the bar 66 moves upward, and this will determine the lower limit of travel of the carriage and the spike.

Compressed air can then be supplied to hammer 24 in conventional fashion by conduit 144 to cause driving element 142 to intermittently begin to drive the spike 54 downwardly. The elevation of the hammer, the elevation of the spike, and the elevation of my device should then, by predetermined positioning, permit the spike point 57 to be in substantial engagement with the tie 14 before the spike driving operation commences. As soon as the hammer 24 has delivered a few rapid driving strokes to the spike so that the spike has started to enter the tie, the control valve can be moved to its first described position which will allow the compressed air in cylinder 90 and the lower end of cylinder 60 to reverse the path of entry and exhaust out of the open end of bore 114 to the right of piston 116 as viewed in FIG. 5. This will cause the fingers 100 to release their grip on spike 54 and the new supply of compressed air to the top of cylinder 60 will cause the carriage to move back to its uppermost position in slots 76 and 78, as shown in FIGS. 1 and 2. The air hammer and my device can then be simultaneously lowered as the hammer continues to drive the spike 54 into the tie. The cycle can then be repeated for each spike to be driven. Obviously, the air controls of my device could be automatically coordinated with that of the hammer without departing from the spirit of my invention.

Thus, from the foregoing, it is seen that my device will accomplish at least all of its stated objectives.

Some changes may be made in the construction and arrangement of my spike setting device without departing from the real spirit and purpose of my invention, and it is my intention to cover by my claims, any modified forms of structure or use of mechanical equivalents which may be reasonably included within their scope.

I claim:

1. In a spike setting device, a carriage supporting means, a carriage movably secured to said carriage supporting means, movable spike gripping means on said carriage, a spike guide means on said carriage supporting

means capable of receiving a spike and holding it adjacent said gripping means, a first power means on said carriage operatively secured to said gripping means to move said gripping means together at times, and a second power means on said carriage supporting means operatively secured to said carriage to move said carriage and said gripping means away from said spike guide means to a spike driving position.

2. In combination, a hammer device having a driving element, and a spike setting device, comprising, a carriage supporting means connected to said hammer device, a carriage movably secured to said carriage supporting means, movable spike gripping means on said carriage, a spike guide means on said carriage supporting means capable of receiving a spike and holding it adjacent said gripping means, a first power means on said carriage operatively secured to said gripping means to move said gripping means together at times, and a second power means on said carriage supporting means operatively secured to said carriage to move said carriage and said gripping means away from said spike guide means to a position adjacent said driving element.

3. The structure of claim 2 wherein said supporting means has a pair of aligned slots formed therein, and further the carriage includes a pair of arms each movably mounted in said slots.

4. The structure of claim 2 wherein the second power means on said supporting means includes a double acting cylinder operatively connected to an arm pivotally mounted on said carriage supporting means and movably secured to said carriage.

5. The structure of claim 3 wherein the first power means on said carriage includes a cylinder having a plunger, said gripping means includes two spring loaded fingers, and said plunger is adapted to operatively engage said spring loaded fingers.

6. In a spike setting device, a carriage supporting means, a carriage movably secured to said carriage supporting means, spike gripping means on said carriage, a spike guide means on said supporting means capable of receiving a spike and holding it adjacent said gripping means, a first power means on said carriage operatively secured to said gripping means, a second power means on said supporting means operatively secured to said carriage to move said carriage and said gripping means away from said spike guide means at times, a control means operatively connecting the second power means on said supporting means and the first power means on said carriage, and means on said control means for coordinating the movement of said first and second power means.

7. In a spike setting device, a carriage supporting means, a carriage movably secured to said carriage supporting means, two fingers having gripping portions pivotally secured to said carriage, means normally pivoting said gripping portions of said fingers away from each other, a spike guide means on said carriage supporting means capable of receiving a spike and holding it between the normally separated gripping portions of said fingers, a first power means on said carriage operatively secured to said fingers to pivot said gripping portions toward each other at times, and a second power means on said carriage supporting means operatively secured to said carriage to move said carriage and said fingers from a position adjacent said guide means to a spike driving position.

8. In a spike setting device, a carriage supporting means, a carriage movably secured to said carriage supporting means, two fingers having gripping portions pivotally secured to said carriage, means normally pivoting said gripping portions of said fingers away from each other, a spike guide means on said carriage supporting means capable of receiving a spike and holding it between the normally separated gripping portions of said fingers, a first power means on said carriage operatively secured to said fingers to pivot said gripping portions to

ward each other at times, a second power means on said carriage supporting means operatively secured to said carriage to move said carriage and said fingers from a position adjacent said guide means to a spike driving position, and a control means operatively connecting said first and second power means, means on said control means for actuating said second power means on said supporting means and simultaneously intermittently interrupting the actuation of said first power means on said carriage.

10 9. In a spike setting device, a carriage supporting means, a carriage movably secured to said carriage supporting means, spike gripping means on said carriage adapted in one position of said carriage to receive a spike, a first power means on said carriage operatively connected to said spike gripping means to move said spike gripping means to a spike gripping position at times, a second power means on said supporting means operatively secured to said carriage to move said carriage and said gripping means away from said one position to a spike driving position.

15 10. In a spike setting device, a carriage supporting means, a carriage movably secured to said carriage supporting means, two fingers having gripping portions pivotally secured to said carriage, means normally pivoting said gripping portions of said fingers away from each other, a spike guide means on said carriage supporting means capable of receiving a spike and holding it between the normally separated gripping portions of said fingers, a first power means on said carriage operatively secured to said fingers to pivot said gripping portions toward each other at times, a second power means on said carriage supporting means operatively secured to said carriage to move said carriage and said fingers from a position adjacent said guide means to a spike driving position, a control means operatively connecting said first and second power means, and means on said control means to actuate said first power means on said carriage when said carriage is being moved toward said spike driving position, and to render said first power means on said carriage inoperative when said carriage is moving away from said spike driving position.

20 11. In combination, a hammer device having a driving element, and a spike setting device, comprising, a carriage supporting means secured to said hammer device and comprised of an elongated base plate having parallel spaced apart side plates secured to the longitudinal edges of said base plate and extending at right angles thereto, a vertical spike feeding tube secured to said base plate between said side plates and extending from the top of said base plate downwardly to approximately the center thereof, a spike guide means on said carriage supporting means below said spike feeding tube, a carriage movably secured to said carriage supporting means, said side plates each having a slot formed therein aligned with each other, said carriage including a pair of arms each movably mounted in said slots, two fingers having gripping portions pivotally secured to said carriage, means normally pivoting said gripping portions of said fingers away from each other, said spike guide means on said carriage supporting means capable of receiving a spike and holding it between the normally separated gripping portions of said fingers,

25 70 75 a first power means on said carriage operatively secured to said fingers to pivot said gripping portions toward each other at times, a second power means on said carriage supporting means operatively secured to said carriage to move

said carriage and said fingers from a position adjacent said guide means to a spike driving position below said driving element,
 a control means operatively connecting said first and second power means, and adapted to actuate said first power means on said carriage when said carriage is being moved toward said spike driving position, and to render said first power means on said carriage inoperative when said carriage is moving away from said spike driving position, said control means including means for actuating said second power means and intermittently interrupting the actuation of said first power means,
 and means for vertically moving said driving element 15 at times.
